UNITED STATES PATENT OFFICE.

FRANCIS E. SWIFT, OF DAYTON, OHIO.

HEATING-FURNACE.

No. 872,858.

Specification of Letters Patent.

Patented Dec. 3, 1907.

Application filed June 3, 1907. Serial No. 376,996

To all whom it may concern:

Be it known that I, FRANCIS E. SWIFT, a citizen of the United States, residing at Dayton, in the county of Montgomery and State 5 of Ohio, have invented certain new and useful Improvements in Heating-Furnaces; and I do declare the following to be a full, clear, and exact description of the invention, such as will enable others skilled in the art 10 to which it appertains to make and use the same.

This invention relates to heating furnaces, and more particularly to the shape of the interior of the fire-box of the same, whereby it 15 is peculiarly adapted for house heating purposes, and has for its object to provide a device of this kind in which a coking table or bench can be used in any desired position therein relatively to the live fire pockets, 20 either in front, behind, on the sides or above the same, and with or without grates, but more particularly to locating said table between two fires.

In the accompanying drawings, which 25 illustrate the invention, Figure 1 is a front elevation of a furnace embodying my invention; Fig. 2 is a vertical, sectional view taken directly at the rear of the front of the furnace; Fig. 3 is a vertical, longitudinal sectional view; Fig. 4 is a horizontal, sectional view looking downward; and Fig. 5 is a detail view of a pair of grate bars.

Referring more particularly to the drawings, 1 indicates the main frame or shell of 30 the furnace, which constitutes the fire-box and may be built of cast or sheet iron, or partly brick, and in some cases it may be lined with fire clay slab where the iron will not stand such hard firing as that to which it 35 may be subjected.

Suitably located within the furnace are 40 the fire pockets 2, two being shown, one near each side and are preferably provided with suitable grate bars 3. The forward ends of the ash pit 4, under the fire floors, as the 45 bars 3, are closed by suitable doors 5, one or both of which is provided preferably with an auxiliary door, 6, which can be utilized as a damper for controlling the draft. A smaller 50 door 7, is located at the forward ends of the fire floors and preferably extends a few inches above the same, and a few inches below it, according to the size of the furnace.

Located between the fire pockets, and 55 preferably above the same, as shown in the drawings, is a coking table 8, which extends

from a door 9, in the front of the furnace to a back wall 10, which is preferably formed from a slab of fire clay. Located preferably directly to the rear of the back wall 10, is a 60 smoke outlet 11, through which the products of combustion from the fire pockets are permitted to escape.

Where the portion of the furnace directly below the coking table is hollow, as in the 65 present instance, a partition 12, projects forward from an inclined galvanized iron covering or jacket 13, at the rear substantially to the front end of the furnace, but at a slight distance at its edges from the side 70 walls of the fire pockets, and in front whereby a space, 14, is left upon each edge and in front of the partition for the passage of cold air that is permitted to enter the furnace. The cold air preferably enters from under- 75neath the furnace and in the rear, as shown in Fig. 3, and after passing up above the partition, it becomes thoroughly heated and passing up in front of and around the upper part of the furnace it enters hot air pipes 15, 80 by means of which it is conducted to any place that it is desired to have heated.

Where grates are used in the fire pockets, they are preferably constructed as shown in Fig. 5, in which one of the bars is stationary 85 and the other bar is slidably mounted and has its forward end provided with an extension, 16, which projects toward the front wall of the furnace and is provided with an opening 17, which is adapted to be engaged by a 90 hook 17' on a lever 18. The movable bar 16' can be moved so that its openings will be out of register with the stationary bar, thus virtually making a closed bottom, or it can be moved in the opposite direction, so that a 95 space of any desired size may be formed. When the grate is used as above described, the back draft can be taken from the ash pit through the back end of the bars, or if a solid bottom is used or formed by the grate bars, 100 the draft can be taken through an inlet below the bottom of the fire hole.

In building or constructing a furnace embodying my invention, as above described, the walls can be formed of any desired thickness, and the coking table may be built solid of any thickness to suit circumstances, or it can be formed hollow and used for radiating surfaces for hot air purposes and it may be of any shape as narrow and long, or more nearly 105 rectangular, and can be used with or without grate bars. A furnace constructed in

this manner will burn any kind of fuel, as wood, coal, soft or anthracite, even the cheaper kinds of soft slack coal, without danger of the flues clogging or choking up from 5 soot, etc., as all such material is consumed, and the amount of radiating surface that is secured for the size of the furnace is very large. It will hold fire for a long time, and can be filled with fine slack coal and will not 10 accumulate so much gas at once as will cause it to puff or explode, as frequently happens. The draft is very great and it does not require a good chimney to cause it to work well.

15 The hot air chamber formed by the additional covering 19 may be used if desired for hot water or steam, and from which it may be led off by the pipes 15 to suitable radiators in a manner similar to that in which hot air is conveyed through said pipes.

20 Having thus described my invention, I claim:

1. In a furnace for house heating purposes,

a shell provided with fire pockets, a hollow coking table, a partition below said table and between the fire pockets.

2. In a furnace for house heating purposes, a shell provided with fire pockets, a hollow coking table, a partition between the walls of said table and at a distance therefrom at its edges.

3. In a furnace for house heating purposes, a shell provided with fire pockets, a coking-table, a partition below said table and between said fire pockets, and means for passing the draft up through the grates, into said fire pockets.

In testimony whereof I have hereunto set my hand in presence of two subscribing witnesses.

FRANCIS E. SWIFT.
